UNITED STATES PATENT OFFICE

99,501

DESIGN FOR A COMBINED AIR CONDITIONING AND CIRCULATING FAN

Robert W. Devore, Chicago, Ill.

Application August 27, 1935, Serial No. 58,327

Term of patent 7 years

To all whom it may concern:

Be it known that I, Robert W. Devore, a citizen of the United States, residing at Chicago, in the county of Cook and State of Illinois, have invented a new, original, and ornamental Design for a Combined Air Conditioning and Circulating Fan, of which the following is a specification, reference being had to the accompanying drawing, forming part thereof.

Fig. 1 is a view in side elevation of the fan and Fig. 2 is a view in rear elevation of the fan.

I claim:

The ornamental design for a combined air conditioning and circulating fan, as shown.

Signed at Chicago, Illinois, this 24th day of August, 1935.

ROBERT W. DEVORE.
